UNITED STATES PATENT OFFICE.

RUDOLF RYCHIGER, OF THUN, SWITZERLAND.

FIREARM.

1,135,722.

Specification of Letters Patent. Patented Apr. 13, 1915.

Application filed December 9, 1914. Serial No. 876,242.

To all whom it may concern:

Be it known that I, RUDOLF RYCHIGER, a citizen of the Federal Republic of Switzerland, and a resident of Thun, in the Canton 5 of Berne, Switzerland, have invented certain new and useful Improvements in Firearms, of which the following is a specification.

The present invention relates to that class of firearms in which the recoil, due to the 10 firing of a cartridge, is utilized to open the breech, extract and eject the empty shell, insert a fresh cartridge from the magazine, close the breech and cock the piece.

The main object of the invention is to generally simplify the construction of firearms 15 of the type mentioned, and so arrange the several parts as to permit of their being easily and readily dismantled, and also assembled whenever desired.

Another object of the invention is to produce means for rotating the breech bolt and bolt carrier within the receiver, and to provide a simple means to effect such rotation, which does not involve considerable expense 25 in its construction, yet effects the desired operation with certainty, ease and freedom.

A further object of the invention is to provide a simple device to lock the firing pin in its position of full cock, if necessary, thereby 30 avoiding accidental or unintentional firing and at the same time an unintentional opening of the rifle.

With these and other objects in view, which will more fully appear as the nature 35 of the invention is better understood, the same consists in the combination, arrangement and construction of parts hereinafter fully described, pointed out in the appended claims and illustrated in the accompanying 40 drawings, it being understood that many changes may be made in the size and proportion of the several parts and details of construction within the scope of the appended claims without departing from the spirit 45 or sacrificing any of the advantages of the invention.

The invention is illustrated in the accompanying drawings, in which:

Figure 1 is a side elevation of the central 50 portion of a rifle constructed in accordance

with the present invention; Fig. 2 is a vertical section taken therethrough; Fig. 3 is a horizontal section taken through the same; Fig. 4 is a section taken on line 4—4 of Fig. 2; Fig. 5 is a section taken on line 5—5 of Fig. 2; Fig. 6 is a section taken on the same line with the safety mechanism in its operative position; Fig. 7 is a section taken on line 7—7 of Fig. 2; Fig. 8 is a section taken on line 8—8 of Fig. 2; Fig. 9 is a vertical section taken through the base plate or race-way on which the receiver actuated by the recoil moves; Fig. 10 is a plan view of the same; Fig. 11 is a section taken on line 11—11 of Fig. 9; Fig. 12 is a section taken on line 12—12 of Fig. 9; Fig. 13 is a section taken on line 13—13 of Fig. 9; Fig. 14 is a section taken on line 14—14 of Fig. 9; Fig. 15 is a section taken on line 15—15 of Fig. 9; Fig. 16 is a vertical section taken through the magazine carrying plate of the rifle; Fig. 17 is a section taken on line 17—17 of Fig. 16; Fig. 18 is a section taken on line 18—18 of Fig. 16; Fig. 19 is a vertical section taken through the receiver of the rifle; Fig. 20 is a horizontal section taken therethrough; Fig. 21 is an end view of the same; Fig. 22 is a section taken on line 22—22 of Fig. 19; Fig. 23 is a section taken on line 23—23 of Fig. 19; Fig. 24 is a section taken on line 24—24 of Fig. 19; Fig. 25 is a section taken on line 25—25 of Fig. 19; Fig. 26 is a section taken on line 26—26 of Fig. 19; Fig. 27 is a section taken on line 27—27 of Fig. 19; Fig. 28 is a section taken on line 28—28 of Fig. 19; Fig. 29 is a section taken on line 29—29 of Fig. 19; Fig. 30 is a vertical section taken through the breech bolt; Fig. 31 is a horizontal section taken therethrough; Fig. 32 is an end view thereof; Fig. 33 is a section taken on line 33—33 of Fig. 30; Fig. 34 is a section taken on line 34—34 of Fig. 30; Fig. 35 is a section taken on line 35—35 of Fig. 30; Fig. 36 is a section taken on line 36—36 of Fig. 30; Fig. 37 is a vertical section taken through the breech-bolt carrier; Fig. 38 is a horizontal section taken therethrough; Fig. 39 is an end view thereof; Fig. 40 is a section taken on line 40—40 of Fig. 37; Fig. 41 is a section taken on line 41—41 of Fig. 37; 100

- Fig. 42 is a section taken on line 42—42 of Fig. 37; Fig. 43 is a plan view of a portion of a breech-bolt carrier; Fig. 44 is a side elevation, partly in section, of the firing pin; Fig. 45 is a plan view thereof, partly in section; Fig. 46 is an end view of the same; Fig. 47 is a section taken on line 47—47 of Fig. 44; Fig. 48 is a section taken on line 48—48 of Fig. 44; Fig. 49 is a rear elevation 10 of the end piece of the breech-bolt; Fig. 50 is a vertical section taken therethrough; Fig. 51 is a plan view of the same; Fig. 52 is a side elevation of the shell extractor; Fig. 53 is a front elevation thereof; Fig. 54 is a section taken on line 54—54 of Fig. 52; Fig. 55 is a section taken on line 55—55 of Fig. 52; Fig. 56 is a section taken on line 56—56 of Fig. 52; Fig. 57 is a side elevation of the trigger; Fig. 58 is a section taken on line 20 58—58 of Fig. 57; Fig. 59 is a vertical section taken through the sear of the trigger apparatus; Fig. 60 is a plan view thereof; Fig. 61 is a section taken on line 61—61 of Fig. 59; Fig. 62 is a section of the magazine follower; Fig. 63 is a bottom plan view of the same; Fig. 64 is a side elevation of a lever forming the connecting means between the receiver and the breech-bolt carrier; Fig. 65 is a plan view of the same; Fig. 66 is a front elevation of the safety device and the 30 manual breech-bolt operating means of the firearm; Fig. 67 is a section taken on line 67—67 of Fig. 66; Fig. 68 is a section taken on line 68—68 of Fig. 66; Fig. 69 is a side elevation of the means for holding the breech-bolt in its open position after the last cartridge in the magazine has been fired; Fig. 70 is a front elevation of the same; and Fig. 71 is a section taken on line 71—71 of Fig. 70.
- In the drawings, the numeral 80 indicates the stock of the firearm, to which is attached by screws 81 and 82 a base plate or raceway 83, that is provided with projections 84, fitting into mortises in the stock to properly position, in assembling, the said base plate or raceway on the stock. Upon the sides of the raceway there are furthermore formed guiding lugs 85, that are seated 50 in grooves 86 of a receiver 87, into which is screwed the barrel 88 of the firearm. The guiding lugs and the grooves 86 on the raceway and receiver, respectively, permit the said receiver and the barrel attached thereto 55 to move through a small distance relative to the raceway. The screws 81, 82 and furthermore a screw 89 serve also to hold upon the stock the base plate 90 of the magazine 91 and of the trigger guard 92.
- The receiver, in which are arranged the various loading, firing and extracting mechanisms, as will be hereinafter described, comprises a substantially cylindrical casing that 60 is open at its front end, and communicates 65 in the usual manner with the barrel attached thereto. Its rear end is closed by an end-piece 93, that is, preferably, screwed into the same, and has pivoted thereto at 94 a downwardly projecting lever 95, which extends into a recess 96 in the base plate or raceway 83. Between this lever and the end-piece 93 is disposed a strong spring 97 for a purpose hereinafter to be described. The lever 95 serves a twofold purpose, that is, first, it limits the recoil movement of the receiver 87 and the parts carried thereby toward the rear of the stock and, second, it prevents by reason of its being seated in the recess 96 a disengagement of the end-piece from the receiver. The receiver is provided with the usual breech-opening, denoted by the numeral 98. In the receiver is slidably and rotatably disposed a breech-bolt carrier 99, which is cored to receive the breech-bolt 100, that constitutes with the bolt-carrier the breech closure of the firearm. The carrier is provided with an exterior projection 101 and an interior projection 102. The exterior projection is seated in a groove 103 in the receiver 87. This groove is straight at 90 its front portion 104, spiral at its central portion 105, and extends parallel to the longitudinal axis of the receiver from the spiral portion to the end-piece 93, as clearly shown at 106. The inner projection 102 of the bolt-carrier extends into a slot 107 in the breech-bolt, said slot having spiral edges 108, that cooperate with the interior projection 102 of the bolt-carrier in a manner hereinafter to be described. On the breech-bolt 10 are cut exterior mutilated screw threads 109, meshing with interior similar screw threads 110 in the receiver 87. The threads 110 in the receiver run in a direction opposite to that of the spiral portion 105 of the groove 103. The purpose of this arrangement will 105 be explained hereinafter. The breech-bolt is provided with a bore 111, and in this bore is slidably disposed a firing pin 112. This pin is, preferably, made of two easily detachable sections 113 and 114, to allow of an easy replacement in case of breakage. The firing pin is provided with two studs 116 and 117. These studs are disposed in the same plane and are seated in a longitudinal slot 118 in the breech-bolt. The stud 117 continuously bears against the edge 119 of a recess in the rear portion of the bolt-carrier 99, said edge comprising a straight portion 120 running parallel to the rear edge of the bolt-carrier, and a spiral portion 121. The stud 116 is adapted to be seated in a recess 122 in the front portion of the bolt-carrier. Within the breech-bolt is located a firing 115 spring 123, bearing against the firing pin and against an end-piece 124, that closes the rear end of the breech-bolt. This end-piece 125 is detachable and held upon the bolt in any suitable manner, for instance it may be provided with projections 125 that interlock 120 with 130

with recessed flanges 126 on the breech-bolt. The firing spring prevents a disengagement of the end-piece from the bolt. Against the breech-bolt carrier and the end-piece 93 bears the action spring 127, which is compressed by the rearward motion of the breech-bolt carrier and breech-bolt, to bring after the recoil the said breech-bolt and its carrier back to their closing positions.

- 10 In the side of the receiver is formed a recess 128, in which is disposed in a vertical plane a lever 129, that is pivoted at 130 to the base plate or raceway 83. Against the curved front portion 131 of this lever bears 15 the receiver, while its rear edge abuts against the bolt-carrier, thereby causing said bolt-carrier to move toward the end piece 93 when, due to the recoil, the lever 129 is swung by the receiver backward around its 20 pivot.

For removing the spent cartridges, a spring extractor 132 is fixedly mounted upon the breech-bolt. This extractor is provided with an inwardly projecting finger 133, that 25 engages in the grooved rim of the shell of the cartridge for withdrawing the same from the barrel as the breech-bolt moves, due to the recoil, backward, and brings the shell against a stop 134 in the receiver, said stop 30 ejecting the shell through the breech-opening.

The cartridge-magazine 91 is disposed in alignment with the breech-opening. It comprises two parts, that is the magazine casing 35 135, and the removable bottom 136, to which is attached the magazine spring 137, the latter carrying a follower 138. The bottom 136 has a longitudinal slot 139, whereby it is rendered resilient in transverse direction. 40 There is provided upon the front end of the bottom a lug 140, engaging with a recess in the base plate 90, said bottom having also upon its sides lugs 141, that are also adapted to engage with the recesses in the said base plate. In putting the cover in place, first the lug 140 is seated in the corresponding recess, after which the bottom is compressed transversely to permit of a seating of the lugs 141 in their recesses, which lugs will 45 spring into place as soon as the cover is released. With the follower 138 co-operates the bolt stop, that is to say the means for preventing the closing of the breech-bolt after the last one of the cartridges in the 50 magazine has been fired. This means comprises a slide 142, that is seated in a slot 143 in the wall of the receiver, and has upon its inner end a shoulder 144, which is adapted to project into the path of the breech-bolt. 55 A spring 145, carried by said slide and bearing against the receiver, holds the said slide in its lower position (Fig. 7). A finger-piece 146, that projects outside of the receiver, is provided for manually actuating 60 the slide. The shoulder is disposed also in

the path of the follower 138, so that, as the said follower rises in feeding the cartridges into the barrel and as the last one is fired, it will cause the slide to move upward against the action of its spring 145, and bring it thus into the path of the breech-bolt, so that it will act as a stop against the action spring 127, and hold the breech-bolt in its open position to permit of the insertion of cartridges through the breech-opening into the magazine. After the cartridges have been inserted the finger-piece 146 is depressed, whereby the breech is closed.

The firing pin co-operated with a sear 147, that is located within the mortise in the base plate 83, and is provided upon its front end with an upwardly extending shoulder 148, that is normally projected by a spring 149, bearing against the sear and against a lever 150, into the path of the stud 116 on the firing pin. The lever 150 is pivoted at 151 to the sear, and bears with one of its arms against the base plate 83 and with its other arm against the sear. The shoulder 148 is considerably higher at one of its longitudinal edges (denoted by the numeral 152) than at its other longitudinal edge (denoted by the numeral 153). The purpose of this arrangement will be described later. Upon the upper face of the sear are formed two ridges 154 and 155. These ridges form the fulcrums around which the sear swings as it is acted upon by the trigger 156; more particularly it turns first round the ridge 154 and then around the ridge 155. As it can be easily felt upon the trigger as the sear reaches one and afterward the other one of its fulcrums, it is obvious that the firing of the piece can be controlled with absolute certainty. In the trigger 156 is formed a downwardly slanting slot 157, through which extends a pivot pin 158, that is attached to the base plate or raceway 83. In a recess in the trigger is slidably disposed a spring pressed pin 159, bearing against a beveled shoulder 160 upon the base plate or raceway 83. A nose 161 upon the trigger bears against the underface of the base plate 83, while a projection 162 on said trigger is in engagement with the sear 147. It will be observed that, in pulling the trigger, the rear edge of the sear is raised, whereby its shoulder 148 is disengaged from the stud 116 on the firing pin, the firing spring then causing the firing pin to strike and fire the cartridge. The spring pressed pin 159, in co-operation with the slanting shoulder 160, causes the trigger 156 to return to its normal position. The slot 157 is provided in the trigger to permit the trigger to move backward as the recoil takes place. The spring 149 causes the sear to assume its normal position after the firing of the cartridge has taken place. It should be noted that the shoulder 148 on the sear tapers toward its front end. The purpose 100 105 110 115 120 125 130

of this is to permit the stud 116 of the firing pin to ride over the same as the recoil takes place.

The breech-bolt is adapted to be opened 5 manually by a sliding rod 163, that is mounted in guides 164 on the receiver 87, and provided with a handle 165. The sliding rod is rotatably mounted in its guides, and is provided near its forward end with 10 a lug 166, that is in the normal position of the rod (Fig. 5) in engagement with a shoulder 167 of the bolt-carrier. By taking hold of the handle 165 and shifting the rod toward the rear, the carrier and the bolt will 15 be opened in the same manner as if a recoil had taken place. The action spring 127 returns the parts to their normal positions. When the rod 163 is in its normal position, a spring 168 on the receiver engages a notch 20 169 in the said rod, thereby holding the same fixed in position. On the rod is furthermore formed a safety dog 170, that is normally seated in a notch 171 in the receiver. This dog is, upon turning the rod 25 90°, adapted to engage the shoulder 167 on the bolt-carrier. In order to bring the said parts in engagement, it is first necessary to disengage the safety dog from the notch 171 by shifting it rearward. After it has 30 been shifted rearward and given the proper turn, it is forced forward into engagement with a notch 172, that is also formed in the receiver. The distance through which the rod 163 is shifted rearward is greater than 35 the extent of the forward movement. When the parts are in these positions, the spring 168 above-mentioned engages with a notch 173 in the rod 163, thereby holding the said rod locked. It is to be observed that when 40 the rod 163 is for the purpose of disengaging it from the notch 171 shifted rearward, the lug 166 carries with it the bolt-carrier and also the breech-bolt. In shifting it thus rearward, the bolt-carrier and the bolt 45 will be given a partial turn, due to the fact that the projection 101 on the bolt-carrier slides in the spiral portion 105 of the groove 103. As this turning motion is given to the bolt-carrier and the bolt, the stud 116 on 50 the firing pin is moved correspondingly and will abut against the highest point on the shoulder 148 of the sear. When then the rod 163 is turned and shifted somewhat forward, the stud 116 will be brought some- 55 what away from the highest point of the shoulder 148, yet it will be held in a position that a pulling of the trigger will not cause a disengagement of the shoulder 148 from the said stud. The firing pin is thus 60 held safely against unintentional or accidental operation.

The operation of this device is as follows: Let us suppose that the magazine is loaded, the piece is cocked, and furthermore that

the safety device is in its inoperative position, that is to say that the dog 170 on the rod 163 is seated in the notch 171 in the receiver. By pulling the trigger, the shoulder 148 of the sear is disengaged from the stud 116 of the firing pin, so that the said pin, 70 under the action of its spring, strikes and explodes the cartridge. The recoil carries back the barrel and receiver, the bolt-carrier and the bolt. The barrel and the receiver move backward a slight distance, 75 about one-quarter of an inch, the lever 95, abutting always against the rear edge of the recess 96, acting as a stop. The spring 97 becomes then operative, and returns the barrel and the receiver to their normal positions. During the rearward movement, the lever 129 is swung by the receiver backward, and, inasmuch as it abuts against the bolt-carrier, it will cause the same to move correspondingly; more particularly it will 80 cause the same to move rearward, but at the same time it will be given a partial turn, due to the fact that its exterior projection 101 moves in the spiral portion 105 of the groove 103. The bolt is caused to move rearward with the bolt-carrier, but, inasmuch as the threads 110 in the receiver run in a direction opposite to that of the spiral part of the groove 103, the said bolt will be 85 turned in a direction opposite to the direction of rotation of the bolt-carrier. By this 90 turning movement, the bolt is disengaged from the receiver and moves, due to the recoil, backward until it almost abuts against the end-piece 93, thereby compressing the 95 action spring 127. As the bolt-carrier and bolt move backward and are turned in opposite directions, the interior projection 102 on the bolt-carrier rides up on the inclined edge 108 of the recess 107 in the bolt, and at the same time the stud 117 on the firing pin rides up the incline 121 on the bolt-carrier and is brought on the straight-edge 120, whereby the firing spring is compressed 100 ready to project the firing pin. The action 105 spring 127 returns then the bolt-carrier and the bolt to their closing positions, but the shoulder of the sear engages first the stud 116 of the firing pin, thereby holding the piece cocked. The bolt-carrier and the bolt 110 turn then in opposite directions, until the threads 109 on the bolt mesh with the interior threads 110 in the receiver. It is to be observed that during the rearward movement of the bolt, the extractor 132 withdraws the empty shell from the barrel. At 115 the same time obviously a new cartridge rises in front of the bolt, which will during its closing position place the same in proper position within the barrel. The play now 120 described is then repeated until the cartridges in the magazine are exhausted. After the last cartridge has been fired, the 125

follower causes the shoulder 144 on the slide 142 to move into the path of the then open bolt, to hold it in open position for loading.

What I claim is:—

- 5 1. In a recoil operated firearm, the combination with a stock, of a raceway fixedly attached thereto, a recoilable receiver upon said raceway, a breech-bolt carrier rotatably and slidably disposed within said receiver, 10 a breech-bolt upon said carrier adapted to rotate in a direction opposite to the direction of rotation of said carrier, and means carried by said raceway and actuated by said receiver for causing upon recoiling of 15 the latter a sliding and rotating motion of said carrier and bolt within said receiver.
2. In a recoil operated firearm, the combination with a stock, of a raceway fixedly attached thereto, a recoilable receiver upon 20 said raceway, a breech-bolt carrier rotatably and slidably disposed within said receiver, a breech-bolt upon said carrier adapted to rotate in a direction opposite to the direction of rotation of said carrier, and a lever 25 pivoted to said raceway and actuated by said receiver for causing upon recoiling of the latter a sliding and rotating motion of said carrier and bolt within said receiver.
3. In a recoil operated firearm, the combination with a stock, of a raceway fixedly attached thereto, a recoilable receiver upon 30 said raceway, a breech-bolt carrier rotatably and slidably disposed within said receiver, a breech-bolt upon said carrier adapted to rotate in a direction opposite to the direction 35 of rotation of said carrier, and means carried by said raceway acting upon said carrier and operated by said receiver for causing upon recoiling of the latter a sliding and 40 rotating motion of said carrier within said receiver and a corresponding motion of said bolt.
4. In a recoil operated firearm, the combination with a stock, of a raceway fixedly attached thereto, a recoilable receiver upon 45 said raceway, a breech-bolt carrier rotatably and slidably disposed within said receiver, a breech-bolt upon said carrier adapted to rotate in a direction opposite to the direction 50 of rotation of said carrier, and a lever pivoted to said raceway acting upon said carrier and operated by said receiver for causing upon recoiling of the latter a sliding and 55 rotating motion of said carrier within said receiver and a corresponding motion of said bolt.
5. In a recoil operated firearm, the combination with a stock, of a raceway fixedly attached thereto, a recoilable receiver upon 60 said raceway having an interior groove comprising a spiral portion and a straight portion running in the direction parallel to the longitudinal axis of said receiver, said receiver being furthermore provided with in- 65terior mutilated screw threads, the direction of which runs opposite to that of the spiral portion of said groove, a breech-bolt carrier having a fixed projection seated in said groove, a breech-bolt upon said carrier provided with exterior screw threads in mesh 70 with the threads of said receiver, and means carried by said raceway in engagement with said carrier and actuated by said receiver for causing upon recoiling of the latter the projection of said carrier to move along the 75 spiral portion of said groove and a disengagement of said bolt from said receiver.
6. In a recoil operated firearm, the combination with a stock, of a raceway fixedly attached thereto, a recoilable receiver upon 80 said raceway having an interior groove comprising a spiral portion and a straight portion running in the direction parallel to the longitudinal axis of said receiver, said receiver being furthermore provided with 85 interior mutilated screw threads, the direction of which runs opposite to that of the spiral portion of said groove, a breech-bolt carrier having a fixed projection seated in said groove, a breech-bolt upon said carrier provided with exterior screw threads in mesh 90 with the threads of said receiver, and a lever pivoted to said raceway in engagement with said carrier and actuated by said receiver for causing upon recoiling of the latter the projection of said carrier to move along the spiral portion of said groove and a 95 disengagement of said bolt from said receiver.
7. In a recoil operated firearm, the combination with a stock, of a raceway fixedly attached thereto having a recess, a recoilable receiver upon said raceway, and end-piece upon said receiver, a lever pivoted to said end-piece having its free end seated in said 100 recess, and a spring between said end-piece and said lever.
8. In a firearm, the combination with a receiver, of a breech closure slidably and rotatably disposed therein, a firing pin within 110 said breech closure having a stud, a sear having a shoulder tapering in a transverse direction, said stud engaging when the piece is cocked the lower edge of said shoulder, means for shifting and simultaneously rotating said closure and the pin carried thereby, whereby said stud is brought into engagement with the higher edge of said shoulder, and means for locking the elements in such positions, whereby firing is 115 prevented upon actuating said sear.
9. In a firearm, the combination with a mortised base plate, of a sear therein having a shoulder at its front end and two ridges behind said shoulder, means causing the 120 first ridge behind said shoulder to abut against a stationary part of the firearm, and a trigger acting upon the rear end of said 125

sear for elevating said rear end, whereby said sear turns first upon the first ridge behind said shoulder and then upon the second ridge.

- 5 10. In a firearm, the combination with a base plate, of a trigger having a downwardly slanting slot, a pivot pin extending through said slot and into said base plate, a slanting shoulder in front of said trigger,
10 and a spring pressed pin upon said trigger

normally in engagement with the uppermost point of the slanting side of said shoulder.

Signed at Berne, in the county of Berne, Switzerland this 12th day of Nov., A. D. 1914.

RUDOLF RYCHIGER.
